(57) **CLAIM**

The ornamental design for an endoscopic instrument for retrograde biopsy, as shown and described.

DESCRIPTION

FIG. 1 is a front perspective view of an open endoscopic instrument for retrograde biopsy according to the present invention.

FIG. 2 is a front perspective view of a closed endoscopic instrument for retrograde biopsy of FIG. 1.

FIG. 3 is a left view of the open endoscopic instrument for retrograde biopsy of FIG. 1.

FIG. 4 is a left view of the closed endoscopic instrument for retrograde biopsy of FIG. 2.

FIG. 5 is a right view of the open endoscopic instrument for retrograde biopsy of FIG. 1.

FIG. 6 is a right view of the closed endoscopic instrument for retrograde biopsy of FIG. 2.

FIG. 7 is a top view of the open endoscopic instrument for retrograde biopsy of FIG. 1.

FIG. 8 is a top view of the closed endoscopic instrument for retrograde biopsy of FIG. 2.

FIG. 9 is a bottom view of the open endoscopic instrument for retrograde biopsy of FIG. 1.

FIG. 10 is a bottom view of the closed endoscopic instrument for retrograde biopsy of FIG. 2.

FIG. 11 is a front view of the open endoscopic instrument for retrograde biopsy of FIG. 1.

FIG. 12 is a front view of the closed endoscopic instrument for retrograde biopsy of FIG. 2.

FIG. 13 is a rear view of the open endoscopic instrument for retrograde biopsy of FIG. 1; and,

FIG. 14 is a rear view of the closed endoscopic instrument for retrograde biopsy of FIG. 2.

The dashed lines illustrate environment that does not form a part of the present invention, and no claim is made to the material illustrated with dashed lines.
